(57) **CLAIM**

The ornamental design for a paint can attachment with brush holding slot, as shown and described.

DESCRIPTION

FIG. 1 is a perspective view of a paint can attachment with brush holding slot, shown from the top, one end, and one side;

FIG. 2 is a perspective view thereof, shown from the bottom, and the end and side opposite that shown in FIG. 1; and,
FIG. 3 is an enlarged cross sectional view thereof taken along line 3—3 of FIG. 1.
